ATTORNEY

UNITED STATES PATENT OFFICE.

OTTO THIE, OF UNION, NEW JERSEY.

FINGER-RING.

SPECIFICATION forming part of Letters Patent No. 292,963, dated February 5, 1884.

Application filed November 19, 1883. (No model.)

To all whom it may concern:

Be it known that I, OTTO THIE, of the town of Union, in the county of Hudson and State of New Jersey, have invented a new and useful Improvement in Rings, of which the following specification is a full, clear, and exact description.

This invention relates to a ring adapted to hold and diffuse a perfume; and the invention consists, principally, in a ring having a cavity for receiving perfume, and a cover and means for permitting the diffusion of said perfume from out of the cavity.

The invention also consists in the details of construction hereinafter more fully pointed out.

In the accompanying drawings, Figure 1 is a perspective view of my improved ring, showing it opened. Fig. 2 is a longitudinal central section of the same, showing it closed.

Similar letters of reference indicate corresponding parts in both figures.

The letter A represents my improved ring, made of suitable material and ornamentation. The same is provided with a cavity, a, to the rim of which is hinged the cover b, which carries a stone, c, or other ornament. The cover b is provided with a catch, by which it may be locked upon cavity a. The cover b is perforated at d, as shown, to create a passage for

the spread of the perfume. This passage, being under stone c, is concealed from view when the ring is closed.

Into the cavity a is placed any suitable absorbent—such as cotton or the like—dipped in perfume, which will be diffused through perforations d.

In place of the perforations in the cover b, any other outlet for the perfume may be made—as, for example, in the base of cavity a, or between the rim of said cavity and the cover.

This invention may also be applied to bracelets or other articles of jewelry.

I claim as my invention—

1. As a new article of manufacture, the ring A, having cavity a, adapted to receive perfume, and the cover b, and means for permitting the diffusion of said perfume from out of said cavity, substantially as specified.

2. The combination of ring A, having cavity a, with cover b, perforated at d, substantially as specified.

3. The combination of ring A, having cavity a, with cover b, perforated at d and carrying stone c, substantially as specified.

OTTO THIE.
